[57] CLAIM

The ornamental design for a foldable clothes hanger, substantially as shown and described.

DESCRIPTION

FIG. 1 is a front elevational view of a foldable clothes hanger showing my new design, in its folded position; FIG. 2 is a side elevational view taken from the left of FIG. 1;

FIG. 3 is a rear elevational view of FIG. 1;

FIG. 4 is a top plan view of FIG. 1;

FIG. 5 is a bottom plan view of FIG. 1;

FIG. 6 is a rear elevational view thereof, in its open position;

FIG. 7 is a side elevational view taken from the right of FIG. 6;

FIG. 8 is a bottom plan view of FIG. 1;

FIG. 9 is a top plan view of FIG. 6;

FIG. 10 is a front elevational view of FIG. 6.
